UNITED STATES PATENT OFFICE

CHARLES BRAHY, OF NEW YORK, N. Y., ASSIGNOR OF ONE-HALF TO CHARLES E. MARION, OF NEW YORK, N. Y.

AUTOMATIC DISPENSING APPARATUS

Application filed February 21, 1930. Serial No. 430,310.

This invention relates to automatic machines for dispensing articles of merchandise, particularly cans or jars of lubricating oil such as are generally sold at gasoline service stations.

This application is a continuation in part of my applications for automatic liquid fuel dispensers having the following filing dates and serial numbers: March 28th, 1928, Serial No. 265,257; August 28th, 1929, Serial No. 388,956; October 8th, 1929, Serial No. 398,162; October 8th, 1929, Serial No. 398,161.

An object of this invention is to provide a machine that will automatically perform the dispensing operation through the medium of a coin actuated mechanism. Another object of my invention is to provide means in an apparatus of this type, of storing the article to be dispensed in quantity, and of permitting the withdrawal of such articles one at a time. A further object is to provide a construction that will render the machine inoperative after all the articles have been dispensed and the machine is empty. A still further object of this invention is to provide means to prevent the insertion of a coin during the dispensing operation, and to reopen the deposit slot after the completion of the dispensing cycle. Other objects and features will appear from the drawings and description hereinafter given.

Referring to the drawings,

Fig. 1 is a vertical sectional elevation of my invention.

Fig. 2 is a sectional elevation taken along line 2-2 of Fig. 1, and showing a portion of the tripping mechanism constituting part of this invention.

Fig. 3 is a rear sectional elevation taken along line 3-3 of Fig. 2.

Fig. 4 is a fragmentary elevation of a portion of the tripping mechanism of Figs. 2 and 3, showing the arrangement of parts immediately after the completion of the tripping operation.

Fig. 5 is a fragmentary part sectional plan view of the machine of Fig. 1, parts being broken away to show the interior construction.

Fig. 6 is a front elevation. Fig. 7 a side elevation, and Fig. 8 a plan view of the enclosed apparatus.

In the drawings, the coin slot 1, superimposed upon the casing 2, connects with the coin chute 3 through the space 4, the said chute terminating above the rotatable balanced temporary coin receptacle 5, which is more fully described in the prior applications above referred to and of which this is a continuation in part. The stems 6 and 7 attached to the receptacle 5, carry the contact points 8, which are electrically connected to the contacts 9, a lamp 10, the resistance 11, the low voltage solenoid 12, the contacts 15, the motor 16, and the lines I and II. This electrical construction is fully described and made a part of the prior application Serial No. 398,162 hereinbefore mentioned; hence a detailed description thereof will not be repeated in this application, but the various parts constituting such mechanism will be referred to hereinafter whenever it will be necessary to do so in order to adequately describe the operation of this apparatus.

The gear 17, which is in engagement with the worm 18 on the shaft 19 of the motor, carries the vertical shaft 20 and the pinion 21 which is in continuous engagement with the bevel gears 22 and 23. These latter gears 80 are mounted on the shafts 24 and 25 respectively, the pinions 26 and 27 attached to the ends of these shafts being in engagement with the circular rack 28.

The hollow cylindrical carrier 29 contains 85 a peripherally disposed magazine for the storage of the articles to be dispensed which are shown in the drawings as oil containers 30. The said magazine comprises a plurality of cells 31 formed by the walls 32, 33 and 90 the base 34, the front and top of said cells being open. This carrier 29 is superimposed upon the said rack 28 and upon the circumferentially disposed spaced rollers 35. A 95 plurality of guide rollers 36, which are also circumferentially disposed, are in constant abutment with the wall 33 of the carrier 29. The casing 37 completely encloses the said carrier, except that there is an opening 38

therein to permit the withdrawal of the containers 30.

Secured to the wall 33 is the cam 39 which is engageable with the follower 40. This follower, shown as a roller, is attached to one end of the lever 41 pivotally connected at 42, the other end of said lever 41 being pivotally connected to the rod 43 which passes through the helical spring 44, and is attached thereto at the point 49. The lever 45 is pivotally attached at its lower end to the rod 43, and at its upper end to the rod 46 which in turn is pivotally connected to the lever 47, the free end of which is engageable with the shutter 48.

Clamped to the shaft 24 are the arms 50 and 51, each of which carries at its end the loosely mounted member 52 having thereon the three fingers, 53, 54, and 55. A stop 56 is fixed to each of the arms 50 and 51 and is positioned between the fingers 53 and 54. The finger 55 is engageable with the roller 57 at the lower end of the bent lever 58 which is pivotally connected at 59. The rod 60 is pivotally attached at its lower end 61 to the lever 58, and at its upper end 62 to the lever 63. The tripper rod 64 is pivotally connected to the lever 63 and the arm 65 which is fixed to the shaft 66 on which the temporary coin receptacle 5 is mounted. Fixed to the said tripper rod 64 is the member 67 which is engageable with the finger 68 of the shutter control member 69. This member 69 is rotatably mounted at 70, the element 71 thereof being in engagement with the shutter 48, the arm 72 protruding into the slot in the coin chute 3 through the opening 73.

When a coin is deposited in the slot 1 it drops into the chute 3, and during its downward passage, forces the arm 72 down, causing a clockwise rotation of the shutter control member 69, so that the element 71 will bring about a movement of the shutter 48 in the direction of the arrow, to close the slot 1. The coin will drop into the temporary receptacle 5, bringing the contacts 8 into abutment, these contacts being normally separated, as fully described in the original application bearing Serial No. 398,162 filed October 8th, 1929. The establishment of an electrical connection at the contacts 8 brings the solenoid 12 into operation, causing an upward movement of the core 74, which results in the breaking of contact at 9 and the making of contact at 13. This shuts off the current through the lamp 10 and closes the circuit through the slow-operating solenoid 14, thereby causing an upward movement of the core 75, and a closing of the circuit through contacts 15 which are in series with the lines I and II and the motor 16. Thus the motor is set into operation.

The rotation of the motor 16 is transmitted to the pinions 26 and 27 through the medium of the gears 18, 17, 21, 22 and 23, and the

shafts 24 and 25. As the pinion 21 is positioned between gears 22 and 23, these latter gears will turn in opposite directions, so that the pinions 26 and 27, located diametrically opposite each other, will likewise turn in opposite directions, thereby imparting a rotary movement to the rack 28 and the attached carrier 29. This revolving movement continues until the tripping mechanism, which will hereinafter be described causes the motor to stop, thereby bringing the carrier to a stop, so that one of the cells 31 with a container 30 therein will be positioned directly behind the opening 38 in the casing 37, to enable said container to be withdrawn.

As the shaft 24 rotates, it carries the arms 50 and 51 with it, so that at the end of every one-half revolution the finger 55 of the member 52 will be brought into engagement with the roller 57. The member 52, being loosely mounted, will rotate until it is brought to a stop by finger 53 coming into contact with the stop 56. As the movement of the shaft 24 continues, the finger 55 will cause lever 58 to swing around its pivot 59, thereby producing a downward movement of the rod 60 against the action of the spring 76. This movement is transmitted through lever 63 to the tripper rod 64, which causes the arm 65 to move in a clockwise direction (Fig. 1) turning the shaft 66 with it, and thereby causing the receptacle 5 to swing downward to drop the coin through chute 77 and into the safe 78.

As the shaft 24 continues to rotate and the finger 55 passes its position of maximum lift of the lever 58, the tension of the spring 76 will cause an upward movement of rod 60 and a consequent downward movement of the roller 57 against the adjacent surface of finger 55. This will cause a sudden rotation of member 52 about its axis until it is brought to a stop by finger 54 coming into contact with stop 56. In this manner the duration of the stay of rod 60 in its projected position is not unduly prolonged, the arm 65 is quickly brought back to its starting position, and the receptacle 5 is consequently permitted to return to its normal position by the action of the weight 79. This weight constitutes the balancing mechanism and is fully described in the above referred to original application. The action of this balancing mechanism causes the contacts 8 to separate, thereby breaking the motor circuit and thus bringing the machine to a stop.

It will be noticed that when the tripper rod 64 is moved in the direction of the arrow (Fig. 1), the member 67 is brought into engagement with the finger 68, causing a counter-clockwise rotation of the shutter control member 69, and a moving of the shutter 48 by the element 71 to the left, to open the slot and thus put the machine in readiness for the next cycle. At the same time the arm 72

is brought back so that it protrudes into the chute 3, in its normal starting position.

In setting the machine for operation, after all the cells 31 have been filled with the

5 articles to be dispensed, the carrier 29 is so positioned that the last cell in the order of rotation will be behind opening 38 when the cam 39 is in engagement with the roller 40. The cam will therefore not come into contact

10 with the roller 40 until the last cell is reached. When this occurs, the said cam will actuate the lever 41 and cause it to rotate about its pivot 42 to produce a movement of rod 43, against the action of spring 44 in the direc-

15 tion of the arrow, thereby causing the lever 45 to produce an upward movement of the rod 46. As the upper end of this rod 46 is pivotally connected to the lever 47, the free end of this lever will engage the shutter 48

20 and move it in the direction of the arrow to close the slot 1. After the cam 39 passes the roller, the spring 44 will bring the rod 43 and the lever 41 back to their normal positions. Thus, after the last cell is reached and the 25 entire magazine is empty, a coin cannot be deposited until the apparatus is reset and refilled.

Other modes of applying the principle of my invention may be employed and different 30 mechanical forms may be embodied therein, the scope of this invention not being limited to the particular form herein described.

What I claim is:

1. In an automatic dispensing apparatus, 35 a rotatable magazine for containing articles to be dispensed, a casing provided with a coin deposit slot and completely enclosing said magazine except for an opening at the delivery position, driving means for actuating said rotatable magazine, coin operated means for actuating said driving means, a temporary coin receptacle, a coin slot shutter, a shutter control member operable upon said shutter and actuated by a coin deposited in said slot to close said slot, and means operable by a single manipulation of said driving means for simultaneously actuating said temporary coin receptacle and operating said shutter control member to open said slot.

50 2. In an automatic dispensing apparatus, a rotatable magazine comprising a plurality of cells, a casing provided with a coin deposit slot and completely enclosing all of said cells but one at the delivery position, driving 55 means for actuating said magazine and intermittently positioning it at its delivery position, coin operated means for actuating said driving means, a temporary coin receptacle, a coin slot shutter, a shutter control member 60 in engagement with said shutter and operable by a coin deposited in said slot, and means operable by a single manipulation of said driving means for simultaneously tripping said temporary coin receptacle and actuating 65 said shutter control member to open said shut-

ter and bring said control member in a position adapted for cooperative relation with a deposited coin.

3. In an automatic dispensing apparatus, 70 a rotatable cylindrical carrier having a peripheral magazine for containing articles to be dispensed, a casing provided with a coin slot and completely enclosing said magazine except for an opening at its delivery position, a coin slot shutter, a coin slot shutter control member actuated by a coin deposited in said slot to close the slot, a temporary coin receptacle, driving means for actuating said carrier, coin controlled means for operating said driving means, said driving means containing a circular rack attached to said carrier and actuated by geared means operatively connected with means for simultaneously actuating said temporary coin receptacle and operating said shutter control member to 75 open said slot.

4. In an automatic dispensing apparatus, 80 a rotatable cylindrical carrier having a peripheral magazine for containing articles to be dispensed, a casing provided with a coin slot and containing said carrier, a coin-slot shutter, a coin slot shutter control member actuated by a deposited coin for closing said slot, a temporary coin receptacle, supporting 85 means for said carrier, a circular rack attached to said carrier and in engagement with two diametrically opposite pinions, said pinions being operable by geared means connected to driving means, coin controlled 90 means for actuating said driving means, said geared means containing a shaft to which is secured an arm, means operatively engageable with said arm adapted to simultaneously 95 actuate said coin receptacle and operate said shutter control member to open said slot.

5. In an automatic dispensing apparatus, 100 a casing provided with a coin slot, a rotatable magazine for containing articles to be dispensed, a coin-slot shutter, a coin slot shutter control member actuated by a deposited coin for closing said slot, a temporary 105 coin receptacle, geared driving means for imparting a rotary motion to said magazine, coin-controlled means for actuating said driving means, said geared driving means 110 containing a shaft to which are secured a plurality of arms each having at its extremity a loosely mounted member with three fingers thereon, two of which are engageable with a stop fixed to said arm, means adapted to simultaneously actuate said coin receptacle and operate said shutter control member to open 115 said slot, a lever operatively connected with said latter means, the third finger being engageable with said lever, said latter means 120 being normally inoperative but adapted to function by a partial turn of said shaft to bring one of said arms in cooperative relation with said lever.

6. In an automatic dispensing apparatus, 125

a rotatable carrier having a cylindrical wall and a peripherally disposed magazine for containing articles to be dispensed; a casing completely enclosing said magazine except for an opening at its delivery position; a coin chute; a temporary coin receptacle; a coin slot shutter; a pivotally mounted shutter control member having an element in operative engagement with said shutter, and an arm extending into said chute for cooperative engagement with a deposited coin for moving said shutter to its closed position; independent means to actuate said shutter; a cam fixed to the inner surface of said wall and operatively connected with said independent means; geared driving means for imparting a rotary motion to said carrier; coin-operated means for actuating said driving means; means operatively connected with said driving means for simultaneously actuating said temporary coin receptacle and operating said shutter control member to open said slot; and means for delivering to the opening in said casing one article at a time.

25 In testimony whereof I affix my signature.
CHARLES BRAHY.
